ERNEST L. WYLIE AND EDWARD H. MOHME, OF ST. LOUIS COUNTY, MISSOURI

FRONT MOTOR MOUNTING

Application filed July 9, 1932. Serial No. 621,638.

This invention relates to a novel device produced in pairs, for supporting the front end of the motor of a Model "A" Ford car.

As received from the factory, the front end of the motor of this car is cushioned by means of coil springs. While such springs answer the purpose for which they are installed, it is well known to all users of this type of car that the constant vibration of the springs produces crystallization after a greater or less length of time, with the result the springs break, and new springs have to be substituted.

It is the object of our invention to substitute rubber supports for the coil springs and so construct the same that they may be inserted in position between the motor support and the frame, and thereafter held in such position, without the necessity of removing the fan belt or the motor support, or loosening the fan pulley, which are necessary operations in installing other forms of cushion devices, and all of which operations are time consuming. The loosening of the fan pulley, in particular, owing to the manner in which this is secured on the crank shaft, presents unusual difficulties, and ordinarily requires the services of a skilled mechanic.

Our invention, in its preferred embodiment, resides in providing a rubber block adapted to seat on the front transverse frame member, said block having at its upper end a retaining member for receiving a lug provided on the under side of the motor support, and having secured in its lower end a holding member projecting from one side of the rubber block and having a hooked end for engaging around the center support bolt 40 which projects downwardly from the under side of the motor support.

The invention is illustrated in the accompanying drawing, in which:

Figure 1 is a view in front elevation of a motor, with the front transverse frame member shown in section, to illustrate the position of parts with a motor supported in accordance with our invention;

Figure 2 is a view on an enlarged scale illustrating, partly in elevation and partly in

section, our improved resilient supports in supporting position, as shown on a smaller scale in Figure 1; and

Figure 3 is a perspective view of the same scale as Figure 2 illustrating one of the supporting blocks.

Referring now to the drawing, the numeral 1 indicates, generally, the motor of an automobile of the type indicated, and 2 a transverse frame member located at the front of the chassis, on which the front of the motor is supported. In practice, that is to say, as the car comes from the factory, there is a yoke member, 3, secured at its opposite ends, as indicated at 4, on the front end of the motor, and coil springs are interposed between this yoke support and the transverse frame member 2. The yoke member 3 has a central depending bolt, 5, and a coil spring is also interposed between the under side of the frame member 2 and a nut secured on the end of the bolt.

By the above arrangement the front end of the motor is yieldingly supported and also cushioned, to a large extent, against imparting its vibrations to the body of the car. The disadvantage of the use of springs, however, is, as stated above, that they very frequently break after a comparatively short length of time, necessitating replacement.

According to our invention, we employ a pair of rubber blocks, 6, of the general tapering shape shown, the under sides of which are shaped to seat on the transverse frame member 2, and the upper end of each of which has fitted on it a cap, 7, having a tubular, upwardly-extending portion, 8, at its center, which is adapted to receive a lug, 9, provided on the under side of the yoke member 3. Vulcanized at one end in each of the rubber blocks 6 is a metal plate, 10, which projects inwardly from one side of the rubber block and is provided at its outer end with a hook, 11, which, when the rubber block is in position, fits around the bolt 5, and thus acts as a holding member to maintain the block in position. As shown by Figure 2, when the two blocks are in position the hooked ends 11 overlap each other. The yoke support 3 has a central depending member

12 provided with an expanded lower end, 13, from the central portion of which the bolt 5 depends. Mounted on the bolt 5 to engage the under side of the transverse frame member 2 is a rubber block, 14, which is held in position by means of a washer, 15, applied to its under side and held in engagement therewith by a nut, 16, screwed on the lower end of the bolt 5. The rubber blocks 6 and 10 14 take the place of the coil springs of the standard construction, and serve to adequately cushion the front end of the motor while, of course, avoiding the element of breakage, incident to the use of springs.

15 By providing the individual blocks with the separate holding members 10 having hooked ends for engaging the bolt 5, we make it possible to substitute these rubber blocks for the coil springs by the simple process of 20 removing the nut 16 and jacking up the front end of the motor about a half an inch, which permits the springs to be removed and the blocks to be substituted therefor. This is made possible by the fact that the 25 blocks can be readily turned to a proper position to be inserted in the space between the underside of the yoke support 3 and the upper side of the frame member 2, while at the same time the hooks 11 may be engaged 30 with the bolt 5. We thus avoid the time-consuming operations of removing the fan belt, changing the position of the fan pulley and removing the yoke support 3, which operations have heretofore been deemed necessary in substituting other cushion members 35 for broken springs.

We claim:

1. A pair of front motor supports each of which comprises a block of resilient material, a lug receiving member mounted on the upper end of said block, and a metal member secured to said block near its opposite end and projecting from the inner side thereof, said member having a holding means 45 provided at its outer end.
2. A pair of front motor supports each of which comprises a rubber block, a lug-receiving member mounted on the upper end of said block, and a metal plate mounted in the lower 50 end portion of the block and projecting from the inner side thereof, said plate having holding means provided at its outer end.
3. A pair of front motor supports each of which comprises a rubber block, a lug-receiving member mounted on the upper end of said block, and a metal plate mounted in the lower end portion of the block and projecting from the inner side thereof, said plate having a hooked outer end.
4. The herein described means for supporting the front end of a motor comprising, in combination with a front frame member, a supporting member secured to the motor and provided with a central depending bolt 65 projecting through an aperture in said frame

member, and having a pair of lugs located, respectively, on opposite sides of said bolt, a pair of rubber blocks supported on said frame member and each of which is provided at its upper end with means for receiving one of said lugs, a metal plate mounted in the lower end portions of each of said rubber blocks and projecting beyond the inner side thereof and provided with a hooked end engaging around said bolt, and resilient means secured on the lower end of said bolt to engage the underside of said frame member.

In testimony whereof, we have hereunto set our hands.

ERNEST L. WYLIE.
EDWARD H. MOHME.
